UNITED STATES PATENT OFFICE.

WILLIAM H. PAYNE, OF CAMDEN, NEW JERSEY, ASSIGNOR TO ZACHARIAH K. LOUCKS, OF PHILADELPHIA, PENNSYLVANIA.

DESIGN FOR A BOTTLE.

SPECIFICATION forming part of Design No. 25,707, dated June 30, 1896.

Application filed April 14, 1896. Serial No. 587,562. Term of patent 14 years.

To all whom it may concern:

Be it known that I, WILLIAM H. PAYNE, a citizen of the United States, residing in the city of Camden, county of Camden, and State 5 of New Jersey, have invented and produced a new and original Design for a Bottle, of which the following is a specification, reference being had to the accompanying drawing, showing the same.

10 The figure is an elevation of a bottle embodying my design.

The leading feature of my design resides in the bottle-neck and consists of the fluted lower portion marked 1, the expanded convex 15 portion marked 2, having a bead 7 at the

lower edge, the contraction marked 3, the band and expanded portion marked 4, the contracted portion marked 5, surmounted by a lip or upper portion marked 6. The combined effect of the several portions is the outline or contour as exhibited in profile in the drawing. 20

Having described my design and illustrated the same, what I claim is—

The design for a bottle herein shown and 25 described.

WILLIAM H. PAYNE.
